Richard Duren

UNITED STATES PATENT OFFICE.

JOHN M. HOFMANN, OF BROOKLYN, NEW YORK.

DESIGN FOR A RADIO LOUD SPEAKER.

Application filed October 19, 1926. Serial No. 19,417. Term of patent 7 years.

To all whom it may concern:

Be it known that I, JOHN M. HOFMANN, a citizen of the United States, residing in Brooklyn, county of Kings, and State of New York, have invented a new, original, and ornamental Design for Radio Loud Speaker, of which the following is a specification, reference being had to the accompanying drawing, forming part thereof, in which—

Figure 1 is a view in perspective.

Figure 2 is a view in side elevation.

Figure 3 is a top plan view showing my novel design for radio loud speaker.

I claim:

The ornamental design for a radio loud speaker as shown.

JOHN M. HOFMANN. [L. S.]
